UNITED STATES PATENT OFFICE.

ALBERT E. COONEY, OF DETROIT, MICHIGAN, ASSIGNOR TO DODGE BROTHERS, OF DETROIT, MICHIGAN, A CORPORATION OF MICHIGAN.

AUTOMOBILE SUPPORT.

Application filed May 26, 1920. Serial No. 384,309.

To all whom it may concern:

Be it known that I, ALBERT E. COONEY, a citizen of the United States, residing at Detroit, Michigan, have invented certain

5 new and useful Improvements in Automobile Supports, of which the following is a clear, full, and exact description.

My invention relates to decking systems for supporting automobiles in freight cars 10 during shipment, and has for its object the provision of a construction for this purpose of minimum cost and weight, which may be readily set up and taken down, and which provides a large space underneath a 15 supported automobile.

In carrying out the foregoing objects, a feature of my invention consists in providing a structure made of steel, thereby securing lightness combined with strength.

20 Owing to the fact that freight cars differ in width, a further feature of my invention consists in providing a supporting structure having certain of its parts adjustable, whereby these varying widths of 25 cars are compensated for.

Other features and advantages will become apparent from the following detailed description and claims when taken in connection with the accompanying drawings, in which

Fig. 1 is a front elevation of my improved decking structure.

Fig. 2, a rear elevation thereof.

Fig. 3, a side elevation of the same.

35 Fig. 4, a top plan view of one side of the supporting structure for the rear axle of the automobile;

Fig. 5, a top plan view on an enlarged scale of a portion of the rear brackets, 40 showing the adjustable block;

Fig. 6, a side elevation of the parts shown in Fig. 5; and

Fig. 7, a front elevation of the same.

Fig. 8, a modified form of construction 45 showing a cast adjustable block in front elevation; and Fig. 9, a side view of the same.

Referring to the drawings, and especially to Figs. 1 and 3, my invention is shown in 50 position in a freight car having sides 1 and floor 2. Resting upon and extending vertically from the floor on either side of the car are brace members, including a vertical member 3 and a horizontal arm 4, extending at right angles to the mem-

ber 3 from the side of the freight car towards the centre thereof, a diagonal 5 extending from the horizontal arm 4 to the member 3.

As shown in the drawings, the member 3 and arm 4 are made of steel channels though other structural steel shapes such as I beams, angles or T's, may be used if found convenient. If desired, the corner formed by the junction of each member 65 3 and arm 4 may be additionally reinforced by triangular plates 6 suitably secured in place by rivets or bolts. Also, if desired, angle irons 7 and 12 may be provided. Mounted on the horizontal arm 4 of each 70 brace member is a block 8 which is recessed to accommodate one end of the axle of the automobile. Owing to the fact that freight cars vary somewhat in width, it is desirable to provide means to compensate for this, and I therefore preferably 75 provide an adjustment for each of the blocks 8. Each block consists of an inner member made of wood having top and bottom reinforcing plates 9 made of metal. These reinforcing plates may be riveted as shown at 80 10, Figs. 5 and 6, and also secured by through bolts 11 also shown in said figures.

To provide for ready adjustment of the blocks 8 along the horizontal arm 4 of each 85 brace member, an angle iron 12 is secured to the end of each block as shown in Figs. 1, 5 and 6, and a bolt passing through the horizontal portion of each of the angle irons 12 also passes through holes bored at intervals along the channeled arm 4. The block may therefore be moved to position to properly support the automobile by moving the block 8 along the arm 4 and then placing the bolt 13 in the proper hole of 90 the arm 4 and tightening the bolt. In order to hold the block 8 more readily, I provide additional means for securing the block in the position corresponding to any hole to which it is adjusted. This additional securing means is preferably in the form of clamps 14 shown most clearly in Fig. 7. These clamps as shown engage the under side of the block 8, preferably bearing against the plate 9 and bent to engage the 95 under portions of the sides of the channeled member 4. The bolts 11 pass through the clamps 14 so that when said bolts are tightened, block 8 is securely clamped against the arm 4 and serves as an auxiliary means for 100 105 110

holding the block in its various positions of adjustment. Instead of using wooden blocks to support the ends of the axles, the cast construction shown in Figure 8 may be used. The cast block 17 is provided at its inner end with a recess having a Babbitt metal lining 18 formed to fit closely upon the axle. This lining being of soft metal will avoid damaging the finished surfaces of the axle. Attached to the block are the lugs 19 and 20 to which steel braces are attached. As will be noted from the examination of the drawing, the block is provided with guides shaped to fit the horizontal member 4 which in this figure is shown as a T bar. To secure the block in place at the proper distance from the center line of the freight car, the set screws 21 are provided.

20 The supporting braces for one axle of the automobile, preferably the front axle, do not require any lateral bracing to provide against any thrusts. To take care of these thrusts, the brace members for the 25 rear axle of the automobile—in addition to the construction already described—are each provided with a horizontal brace 15, Figs. 3, 4, 5 and 7, said brace 15 being bolted or otherwise suitably secured to the 30 block 8 and to the corner of the freight car. A brace 16 is also provided, said brace engaging the opposite side of the block 8 and extending diagonally downwardly and forwardly to the floor of the freight car, to 35 which floor it may be suitably secured. It will be noted that all of the elements constituting the front brace members are seated in the same vertical plane, and that any thrusts are provided against by means of 40 braces engaging the rear brace members. It will also be noted that by reason of the fact that fewer members are necessary to form a rigid structure, by reason of the use of steel instead of wood, ample space is provided underneath the supported automobile.

What I claim as new is:

1. In an automobile decking system for freight cars, in combination, a brace member for supporting one axle of the automobile, said brace member having its elements substantially in one vertical plane, a second brace member for the other axle, said second brace member comprising a brace extending from the side of the freight car 55 horizontally towards the centre thereof, a brace member extending from said first mentioned member in a horizontal direction to the side of the freight car, and another brace member co-operating with said horizontal arm and extending from the opposite side thereof to the floor of the freight car.
2. In an automobile decking system for freight cars, in combination, a brace member for supporting one axle of the automobile,

bile, said brace member made of steel and comprising a vertical flanged member, a horizontal flanged arm, and a diagonal brace extending between said member and arm and in the same vertical plane therewith. 70

3. In an automobile decking system for freight cars, in combination, a brace member for supporting one axle of the automobile, said brace member made of steel and comprising a vertical flanged member, a horizontal flanged arm, a diagonal brace 75 extending between said member and arm and in the same vertical plane therewith, a second brace member for supporting the other axle of the automobile, and means co-operating therewith for bracing the automobile against end thrusts. 80

4. In an automobile decking system for freight cars, in combination, a brace member for supporting an axle of the automobile, said brace member including an arm extending horizontally from the side of the freight car towards the centre thereof, a block recessed for receiving the said automobile axle, and two separate means for securing said block in each of several positions of adjustment along said horizontal arm. 85

5. In an automobile decking system for freight cars, in combination, a brace member for supporting one axle of the automobile, said brace member including a horizontal arm made of flanged steel, said arm extending from the side of the freight car 100 towards the centre thereof, a block bored for receiving said automobile axle, and means carried by said block-engaging holes in said arm to hold the block in different positions of adjustment along said arm. 105

6. In an automobile decking system for freight cars, in combination, a brace member for supporting one axle of the automobile, said brace member including a horizontal arm made of flanged metal, said arm extending from the side of the freight car towards the centre thereof, a block recessed for receiving said automobile axle, and means engaging said block and the under portions of the sides of said arm for 110 clamping said block at various positions along said arm.

7. In an automobile decking system for freight cars, in combination, a brace member for supporting one axle of the automobile, said brace member including a horizontal arm made of flanged steel, said arm extending from the side of the freight car towards the centre thereof, a block bored for receiving said automobile axle, clamps 115 engaging said block and the under portions of the sides of the arm, and bolts passing through said clamps and said block whereby the latter is secured in different positions along said arm. 120

130

8. In an automobile decking system for freight cars, in combination, a brace member for supporting one axle of the automobile, said brace member including a horizontal arm made of flanged steel, said arm extending from the side of the freight car towards the centre thereof, a block recessed for receiving said automobile axle, a plate carried on the underside of said block, clamps bearing against said plate and bent to engage the under portions of the sides of said arm, and bolts passing through said clamps and said block to secure the latter in different positions along said arm.
9. In an automobile decking system for freight cars, in combination, a brace member for supporting one axle of the automobile, said brace member including a horizontal arm made of flanged steel, said arm extending from the side of the freight car towards the centre thereof, a block recessed for receiving said automobile axle, and means carried by said block for engaging holes in said horizontal arm to hold the block in different positions of adjustment along said arm, and means engaging said block and the under portions of the sides of said arm for clamping said block in position corresponding to any hole.
10. In an automobile decking system for freight cars, in combination, a brace member for supporting one axle of the automobile, said brace member including a horizontal arm made of flanged steel, said arm extending from the side of the freight car towards the centre thereof, a block recessed for receiving said automobile axle, and means carried by said block for engaging holes in said horizontal arm to hold the block in different positions of adjustment along said arm, and means engaging said block and the under portions of the sides of said arm for clamping said block in position corresponding to any hole.

Signed at Detroit, Michigan this 22nd day of April, 1920.

ALBERT E. COONEY.
